UNITED STATES PATENT OFFICE

BENJAMIN L. INGRAM AND WILLIAM H. DE LONG, OF MENARD, ILLINOIS

WINDOW

Application filed September 26, 1928. Serial No. 308,391.

This invention relates to window construction, and aims to provide an all metal double sash window, wherein either sash can be raised or lowered, or swung inwardly to facilitate cleaning both sides of the window pane from the interior of the room, the entire construction being such that it can be easily and cheaply installed in either new or old buildings of any type.

10 Another object of the invention resides in the provision of a window construction that is weather tight, and one which is both strong and durable, the sashes being equipped with means for automatically locking the sashes in any desired opened position for ventilation, or in their fully closed position whereby the sashes cannot be opened from the outside.

20 The nature and advantages of the invention will be better understood when the following detail description is read in connection with the accompanying drawings, the invention residing in the construction, combination and arrangement of parts as claimed.

25 In the drawings forming part of this application like numerals of reference indicate similar parts in the several views, and wherein:

Figure 1 is a view in elevation of the 30 window construction in accordance with the present invention.

Figure 2 is a sectional view on line 2—2 of Figure 1.

Figure 3 is a sectional view on line 3—3 35 of Figure 1.

Figure 4 is a sectional view on line 4—4 of Figure 1.

Figure 5 is a sectional view on line 5—5 40 of Figure 1.

Figure 6 is a sectional view on line 6—6 of Figure 1.

Figure 7 is a sectional view on line 7—7 45 of Figure 6.

Figure 8 is a sectional view on line 8—8 of Figure 1.

Referring to the drawings in detail, 10 represents the window casing, the opposed sides of which are provided with longitudinal grooves to accommodate the upper and lower sashes for sliding movement, so that either

or both of said sashes can be raised or lowered in the usual manner. As each sash is of the same construction, a detail description of one, will of course, suffice for both.

Each sash includes an outer frame indicated generally at A and which is of angular construction in cross section as clearly illustrated in Figure 4. The flange 11 of each

side of this frame is received in the adjacent groove of the casing to support the sash for sliding movement, and each flange 11 is provided with a vertical series of spaced openings 12 for a purpose to be hereinafter described. The other flange 13 at each side of this frame engages the adjacent side of the casing 10. Each sash also includes inner frames indicated generally at B and of angular formation in cross section as clearly illustrated in Figure 4. The flange 14 of this frame B is secured in any suitable manner to the flange 13 of the frame A, while secured to the flange 14 of the frame B is a retaining strip 16 of any suitable material for holding the panes 17 on the inner frame B. Strips of weather tight material 18 are arranged at the opposite sides of the panes 17 and are clamped between the flange 15 and the retaining strip 16 as clearly illustrated in Figure 4. Both the inner and outer frames of each sash slides as a unit in the window casing 10 so that the sashes can be raised or lowered in the ordinary well known manner, but upon inspection of Figure 1 it will be noted

that the inner frame B of each sash is hingedly mounted at 19 upon the outer frame A, so that the inner frame of the sash can be swung inwardly to permit the window pane 17 to be quickly and readily cleaned on both sides from the interior of the room. Each inner frame B is provided with a suitable latch 20 for holding this frame fixed with relation to the outer frame A.

As clearly illustrated in Figures 1 and 5 the outer frame A of each sash is formed with centrally located cross bars 21 of substantially T-shaped formation in cross section. The central or intermediate flange 22 of each of these bars is preferably hollow as illustrated in Figure 5 for lightness in construction, and as illustrated the adjacent panes 17 en-

gage the opposite sides of this intermediate flange 22. Weather tight strips of suitable material are arranged at the opposite sides of the panes 17, and the parts are all held associated by a retaining bar 24, the latter having an intermediate closed portion 25 to accommodate itself to the intermediate flange 22 of the bar 21. Suitable fastening elements 26 hold the retaining bar 24 associated with the intermediate flange 22 as shown.

By reason of the construction herein shown and described, it will be manifest that the window construction is an all metal construction, and that the component parts can be stripped in a knocked-down condition and quickly and conveniently assembled for installation. Furthermore, the window construction can be used on any type of old or new building, the entire construction being very light, yet strong and durable.

In accordance with the present invention we also contemplate a novel construction of means for automatically locking the window sashes in any given position, so that the sashes can be raised or lowered a slight distance for ventilating purposes, or when the sashes are locked in their fully closed position they cannot be opened from the exterior of the building. This locking means is clearly illustrated in Figures 6 to 8 inclusive, wherein it will be noted that the locking means is actuated by push-buttons 27. There is one of these mechanisms at each side of the window casing as illustrated in Figure 1, and the push-button 27 is carried by the lower end of a link 28 which is pivoted at a point between its ends as indicated at 29. The push-button 27, of course, slides through an opening in the window casing, while the opposite end of the link 28 supports at a right angle thereto a locking bolt 30.

Exerting a pressure against the link 28 in a line with the locking bolt 30 is a spring 31 which functions to project the locking bolt into one of the openings 12 formed on the flange 11 of the outer casing A of the sash. Consequently when either sash is raised or lowered to the desired extent, the locking bolt 30 will engage one of these openings 12 thereby locking the sash or sashes against movement. In order to release the sash or sashes it is only necessary to press against one or both of the push-buttons 27 as will be readily understood. It will be noted that the locking mechanism for the upper sash is indicated in Figures 6 and 7, while Figure 8 indicates the same mechanism for the lower sash. However, in Figures 6 and 7 the locking bolt 30 is formed with an intermediate crank like portion to pass around the grooves which receive the sashes, the crank portion being indicated at 32. Otherwise both locking mechanisms are the same.

While it is believed that from the foregoing description the nature and advantages

of the invention will be readily apparent, we desire to have it understood that we do not limit ourselves to what is herein illustrated and described and that such changes may be resorted to when desired as fall within the scope of what is claimed.

What we claim is:

1. A window construction including a casing having sash receiving grooves, upper and lower sashes, each sash including inner and outer frame sections of L-shaped formation in cross section, the outwardly directed flange on the outer section being slidably received in one of said grooves, the forwardly directed flange of the same section being in contact with said casing, the forwardly directed flange of the inner section lying in contacting engagement with the corresponding flange of the outer section, the inwardly directed flange of the inner section constituting a support for the glass pane of the window, means for securing the said glass pane to the last mentioned flange, and means for supporting the inner frame upon the outer frame for swinging movement.

2. A window construction including a casing having sash receiving grooves, upper and lower sashes, each sash including an inner and outer frame of L-shaped formation in cross section, the outwardly directed flange of the outer frame being slidably received in one of said grooves, the forwardly directed flanges of said frame contacting the window casing throughout their length, the forwardly directed flange of the inner sash lying in contacting engagement with the corresponding flange of the outer sash, the inwardly directed flange of the inner sash being utilized to support the pane of glass, and centrally located cross bars of T-shaped formation in cross section forming part of the inner frame, and having their intermediate flanges cooperating with said inwardly directed flanges of the inner sash for the purpose specified.

In testimony whereof we affix our signatures.

BENJAMIN L. INGRAM.
WILLIAM H. DE LONG.
